UNITED STATES PATENT OFFICE.

LESLIE ELVIN WILLIAMS, OF WICHITA FALLS, TEXAS, ASSIGNOR OF ONE-HALF TO CLIFFORD ALLDAY, OF PETROLIA, TEXAS.

CHANGEABLE-LETTER SIGN.

Application filed December 5, 1922. Serial No. 305,070.

To all whom it may concern:

Be it known that I, LESLIE ELVIN WILLIAMS, a citizen of the United States, residing at Wichita Falls, in the county of 5 Wichita and State of Texas, have invented a new and useful Changeable-Letter Sign, of which the following is a specification.

The invention relates to a changeable letter sign to be built of metal or any other 10 suitable material, being provided with pillars and supporting bars, said supporting bars being parallel with said pillars with any desired number of adjustable bars arranged transversely thereon. The object of 15 the invention is to provide a device of this nature to be used either as an interior or exterior sign, the lettered plates having hook arrangements thereon which hold them to the adjustable bars.

20 Another object of the invention is to provide a device of this nature having lettered plates with hook arrangements thereon, said lettered plates being of various sizes. Said adjusting bars may be adjusted to fit any 25 size lettered plate.

Another object of the invention is to provide a device of this nature which is very simple and practical and can be manufactured at a very nominal cost.

30 The nature and advantages of the device will be better understood when the following detailed description is read in connection with the accompanying drawing, forming a part of this application. The invention residing in the construction, combination and arrangement of parts as claimed.

In the accompanying drawing the various parts will be referred to by numbers.

40 Figure 1 is a front plan view of the device.

Figure 2 illustrates the arrangement of the hooks on the lettered plates.

Figure 3 illustrates the method of locking the lettered plates to the sign.

45 Figure 4 is a side view, showing the plates arranged on the adjustable bars.

The device forming the subject matter of this invention comprises the frame 1, which consists of several pieces of metal or other 50 suitable material, fastened together with braces as illustrated at 2. The frame is supported by two main pillars which are anchored at the bottom in a concrete base. The pillars 4 and 5 are merely ornamental. The

supports 6 are arranged at an equal distance 55 between the pillars 3. The adjustable bars 7 are slidably fastened to supporting bars 6 with bolts as illustrated at 8. The lettered plates may be small as illustrated at 9 or may be large sheets as illustrated at 10. The upturned hooks 11 engage the locking bars 12 and prevent the plates from being removed by unauthorized persons. It will be noted that the locking bars are slidably bolted in the vertical grooves of the supports 6. 60 The hooks 14 turned downward are for the purpose of holding the plate to the sign. The braces 13 hold the sign rigid. The notched teeth on the bar 18 hold the adjustable bars 7 and the locking bars 12 to any 65 position in which they may be placed. The bar 18 is hooked into a stationary eyelet 15 at the top of the sign and the bottom of the bar 18 is slipped over a stationary eyelet 16 and held securely in place with a lock 17. 70 The ends of the bars 7 and 12 fit into the notched teeth of the bar 18. The opposite ends of the bars 7 and 12 fit into holes in a stationary bar. The plates 9 are provided with a blank space around the lower and 75 righthand side, said blank space to fit under the adjoining letter plates, thus closing the gap between the different lettered plates. When in position for use this arrangement provides a very attractive sign. The word- 80 ing on the sign may be arranged with the lettered plates 9, which may be of any desired size as the bars 7 may be adjusted to fit any size lettered plate, or the sign may be covered with sheets of metal or other 85 suitable material, as illustrated at 10 in Figure 2, thus providing a surface for painting or pasting paper signs upon. The lettered plates 9 cannot be removed from the sign without the key to the lock 17, thus preventing anyone who is not authorized or 90 who does not have a key from molesting the sign.

While it is believed from the foregoing description the nature and advantages of 100 the invention will be readily apparent, I desire to have it understood that I do not limit myself to what is herein shown and described, and that such changes may be resorted to when desired as fall within the 105 scope of what is herein claimed.

What I claim is:

1. A changeable letter sign comprising a

frame, a pair of anchored pillars supporting said frame, a plurality of vertical spaced bars attached to said frame, transverse bars slidably attached to said vertical bars, letter plates having hooks disposed opposite to each other thereon, means for locking said slidable transverse bars to prevent unauthorized vertical movement thereof.

2. A changeable letter sign comprising two pillars, a metal frame mounted between said pillars, vertical spaced supporting bars attached to said frame, oblique disposed bracing bars between said spaced vertical bars, transverse bars slidably attached to said vertical supporting bars, letter plates having upward and downward turned hooks thereon to engage the adjustable transverse bars, the ends of said transverse bars engaged in a vertical bar having a plurality of apertures therein, said vertical apertured bar being removably attached to said frame,

means for locking said vertical apertured bar to said frame.

3. A pair of pillars, a frame mounted on said pillars, vertical supporting bars attached to said frame, oblique disposed bracing bars between said supporting bars and frame, a plurality of transverse bars adjustably attached to said vertical supporting bars, plates having opposite to each other turned hooks thereon to engage the transverse adjustable bars, a locking device comprising a vertical bar having a plurality of notches therein to engage pointed ends of the adjustable transverse bars, means for attaching and locking said vertical notched bar to the end of said frame, as shown and described.

LESLIE ELVIN WILLIAMS.
